STRIPING MACHINE FOR STRAND MATERIAL

George E. Forsberg, Worcester, Mass., assignor to
Surprenant Mfg. Co., Boston, Mass.

Application April 29, 1949, Serial No. 90,391

5 Claims. (Cl. 118—222)

1

This invention relates to improvements in striping machines adaptable for instance to the placing of distinctive marks or stripes on electric conductors or wires and it is the general object of the invention to provide for automatically regulating the amount of striping ink flowing to a moving part of such a machine from a stationary ink supply.

A striping machine which I have already proposed, shown in copending applications Serial No. 784,025, filed November 4, 1947, now Patent No. 2,537,884, and Serial No. 82,732, filed March 22, 1949, includes a rotatable striping unit having built therein ink wells communicating with inking pockets or chambers in which striping discs turn due to peripheral engagement with the wire being striped as it moves along the axis of the machine. The striping capacity of that machine for any period of continuous operation is limited to the amount of ink which the wells can hold and when it is desired to stripe a long piece of wire it is necessary to stop the machine and replenish the ink supply manually.

It is an important object of the present invention to provide striping mechanism including one or more stationary reservoirs or tanks of ink to feed or supply ink to the inking pockets through ink receivers turning with the unit, and automatically control the delivery of ink from each stationary source to the corresponding receiver and pocket so that ink will flow into any given pocket at a rate proportionate to that at which the ink in it is used up by its striping disc.

It is a further object of the invention to deliver ink from each tank into its receiver through a delivery means the mouth of which is located within an ink receiving compartment in the receiver and connect the compartment to its associated ink pocket in such manner that when sufficient ink is present in the pocket it will maintain a sufficient depth or level of ink in the compartment to prevent flow of ink from the tank, but when the level of ink in the pocket falls due to consumption by the disc there will be a corresponding drop in the level of ink in the compartment and ink will be able to flow into the latter to maintain the desired level or depth of ink in the pocket. This control is effected by changes in two forces at the mouth of the delivery member, one of these forces being derived from the normal tendency of the ink to flow into the compartment, and the other being derived from rotation of the ink in the compartment.

It is a further object of the invention to provide improved ink receiver means built up of a plu-

2

rality of ring like members each complete in itself and having an ink receiving compartment contained therein. These ring members are arranged one over the other and communicate by appropriate passages with their corresponding ink pockets.

Since it is essential that ink in the compartment shall be rotating in order to oppose flow of ink from the delivery member it is a further object of the invention to provide the compartment with ribs, vanes, or the like which will assist in causing the ink in the compartment to rotate around the axis of the machine.

When it is necessary to stop the machine there will ordinarily be some striping ink in the compartments and inking pockets, and in order that this ink may be adequately handled without mixing in the rotatable unit as the latter slows down, it is a further object of the invention to provide

10 the unit with catch wells, one for each pocket, into which the ink can flow as the machine comes to rest. These wells differ from the wells previously proposed by me in that they are not primarily sources of the striping ink, but are present merely

15 to receive ink from the pockets when the machine is stopped. The ink depth or level in the pockets will ordinarily be such that the ink cannot enter the wells while the machine is in operation. If it is desired to restart the machine after stopping the ink previously delivered into the wells will be returned by centrifugal force to the inking pockets.

20 With these and other objects in view which will appear as the description proceeds, the invention resides in the combination and arrangement of parts hereinafter described and set forth.

25 In the accompanying drawings, which show a convenient embodiment of the invention,

Fig. 1 is a front elevation of a machine made

30 according to the present invention,

Fig. 2 is an enlarged horizontal section on line

35 2—2, Fig. 1,

Fig. 3 is a vertical section on line 3—3, Fig. 2,

Fig. 4 is a horizontal section on line 4—4, Fig. 3,

40 parts being omitted and part of the structure

45 being broken away to show one of the inking pockets,

Fig. 5 is a horizontal section on line 5—5, Fig.

45 3, and

Fig. 6 is a diagrammatic view showing the manner

50 in which the invention operates.

Referring particularly to Fig. 1, the striping machine comprises a frame 10 having a top or

55 table 11 which supports the striping unit designated generally at U. A motor M supported on

the frame acts through a belt 12 to turn a pulley 13 secured to the lower end of the unit. The wire W to be striped is wound on a reel 14 which turns to supply the wire at the rate required. Take-up mechanism not shown herein but similar to that set forth in prior applications filed by me operates to draw the wire upwardly along the axis of unit U as the latter rotates. The rate at which the wire moves can be varied so that the length of the lay of the stripe or stripes being produced can be changed. It is not thought necessary to show the take-up mechanism herein and it is believed to be sufficient to state that during operation of a machine the unit U will rotate as the wire moves through it.

Referring more particularly to Fig. 3, the table has mounted thereon a block 15 and bearing member 16, and has on the underside thereof a second bearing member 17, the block and bearing members being held to the table by bolts 18. A hollow shaft 19 is rotatably mounted to turn about a vertical axis in upper and lower ball bearings 20 mounted on the bearing members. The shaft 19 has a bore 21 through which extends a stationary guide tube 22 within which the wire W travels. A guide 23 at the top of tube 22 serves to direct the wire along the axis of the unit U.

The rotating unit includes a base 25 and a head block 26 secured thereto by screws 27. The upper part of shaft 19 is screw threaded as at 28 into the bottom of base 25 and set screw 29 holds the base securely on the shaft. The base is formed with chambers three of which are shown herein at 30, and similarly the head block has chambers 31. These chambers radiate from the axis of the machine and their outer ends remote from the machine axis form three inking pockets P1, P2 and P3, see Fig. 4. The base 25 has an ink catch well 32 formed therein below each ink pocket, these wells have their axes inclined slightly in an upward and outward direction so that ink in a well can by centrifugal force be caused to rise into the associated pocket. Each well may have a drain plug 33 which can be removed for cleaning purposes.

Extending upwardly from the table 11 are arms 35 supporting a platform 36 on which are mounted three tanks or reservoirs 31, 38 and 39 containing striping ink which may be of the same or diverse colors. Each tank has leading therefrom an ink delivery member which may be in the form of a pipe or tube, these delivery members being designated at 40, 41 and 42. A valve 43 in each pipe can be closed when the machine is not in operation and opened to supply ink while the unit U is rotating. Each delivery member has a mouth 45 through which ink can flow in a direction either toward or from the associated tank.

Mounted on top of the head block 26 is an ink receiver means R made of a plurality of ring like ink receiver members concentric with the axis of unit U and secured to the head block by screws 50. These members are designated at 51, 52 and 53 and correspond respectively to ink pockets 54, 55 and 56. Each of the ring members has a vertical circular wall 57 and an ink compartment opening preferably inwardly from the wall toward the axis of the machine. These compartments are designated at 60, 61 and 62 and each is formed as a groove in its ring member extending upwardly and inwardly toward the axis, as will be apparent from Fig. 3. Each ink compartment is complete within its own member

and has a circular opening 63 concentric with the machine axis and adapted to receive one or another of the delivery tubes 40-42. Extending into each compartment from the wall 57 thereof are vanes or ribs designated at 65.

The circular vertical walls 57 are provided with three vertical bores 66, 67 and 68 one only of which communicates with the associated ink compartment by means of a passage 69. The members 51-53 are arranged in vertical order one over the other as shown in Fig. 3 with the bores in their walls 57 vertically aligned in groups to form vertical ducts 70, 71 and 72. The ring members are so disposed or staggered angularly with respect to each other that only one of the passages 69 communicates with one of the ducts. Thus, as shown in Fig. 3, the compartment 60 communicates with duct 70 through passage 69 but does not communicate with either of the other ducts. The head block 26 has a plurality of short ink passages 75 entering the upper part of the pockets and registering one by one with the ducts 70-72. Each pocket is, therefore, in communication with but one compartment, and ink in the latter will flow into the former.

The low end of each of the delivery members or tubes 40-42 enters its corresponding compartment and is bent laterally as at 80 in a direction opposite to that in which the unit rotates. Thus, as shown in Fig. 2, tube 42 is bent to the left and the unit rotates to the right in the direction of arrow a, hence any ink in the compartment corresponding to delivery tube 42 will move in a direction toward the mouth 45 thereof.

In operation, the unit will be set in rotation as the machine is started, and the valves 43 then opened, and ink in the tanks will have a tendency to flow through the associated delivery members into the corresponding compartments. This tendency to flow as set forth herein is attained by having the tanks above the unit, the flow force being that derived from gravity, but gravity is not the only force which can be utilized to cause ink to tend to flow from the delivery mouths.

With the valves 43 open ink will flow into the compartments and will flow from the latter into their corresponding inking pockets and be held in the latter spaced from the inking station S by centrifugal force. As ink continues to flow into the compartments the depth of ink in the pockets and compartments will increase so that the wall of the ink will move toward the axis of the machine. When ink in any given compartment attains such a depth as to immerse part of the corresponding ink delivery mouth 45 the force of the ink in the compartment, due to its rotation around the axis, will oppose the normal tendency of ink to flow out of the mouth into the compartment, and when these forces are balanced ink will cease to flow from the associated tank. As the striping operation continues ink will be used up and the depth of ink will diminish and less of the mouth will be immersed in ink in the compartment, whereupon the normal tendency of ink to flow from the tank will again assert itself and reestablish the normal depth of ink in the compartment.

Referring more particularly to Fig. 6, the lines L1 and L2 represent the limits of depth of ink which will normally exist within a compartment. When there is considerable ink in a pocket and its associated compartment, as by rise of residual ink from the associated catch well by centrifugal force, the level of ink, or its depth, may be that

represented, for instance, by line L1 and the greater part or all of the mouth 45 will be immersed in the ink in the compartment. Due to rotation of this ink and the fact that it exerts a greater force in the mouth 45 than that exerted by gravity ink will be forced up the corresponding pipe or tube to the corresponding stationary tank. This process will continue until the depth of ink falls to some such level as that indicated at line L2, whereupon the force exerted by the rotating mass of ink in the compartment will not be able to overcome the gravity force and ink will again flow into the compartment.

While the two lines L1 and L2 have been shown as defining the normal limits of depth of ink in a compartment, it is probable that the actual working depth lies between these two lines at a position determined in part by the rate of rotation of the ink and the radial distance of mouth 45 from the machine axis, and also the head or gravity force tending to discharge ink from the mouth. As the depth of ink in a tank decreases due to use of the ink the pressure due to gravity will diminish. Also, there will be more slip between the rotating receiver ring and a thin ink than a thick ink, so that some variation in pressure exerted at mouth 45 by the rotating ink will exist, depending upon the ink. The vanes 65 are for the purpose of reducing the aforesaid slip. These several factors will all have some bearing on the actual depth of ink in the pockets and compartments.

Because of the connection between each pocket and its compartment the depth of ink in them will have a common level which will change simultaneously in both the pocket and compartment. When the ink in compartment 60, for instance, is at a level corresponding to line L1, Fig. 6, the level of ink in the pocket P1 will be as determined by line L1 in Fig. 3, that is, it will be beyond the corresponding well 32. This will be true of all the pockets and their wells when the machine is running at full speed, and under these conditions the wells will be empty.

When it is necessary to stop the machine the ink flow will be stopped by closing the valves 43, but there will remain in each compartment and its associated pocket some ink which as the machine slows down and centrifugal force diminishes will flow into the associated catch well. Upon resumption of operation ink in any well will be acted upon by centrifugal force and will return to its associated pocket.

It will thus be seen that the flow of ink from each tank into its corresponding inking pocket is self-regulating, the normal pressure tending to cause flow of ink from a tank into its compartment being less than the pressure exerted by the rotating mass of ink in the compartment, and these pressures being exerted over changing areas of the mouth 45 so that the forces exerted at the mouth will cause ink to flow out of or into the mouth. Even though slight vibration of the machine should cause alternating inflow and outflow, there will be an average outflow just sufficient to replenish the ink used to stripe the wire.

To illustrate a means by which ink in the pockets can be transferred to the wire to stripe it there is shown herein an inking disc arrangement similar to that shown in the previously mentioned copending applications. Three discs 85, 86 and 87 are provided, one for each inking pocket, each disc being of large enough diameter so that the outer part of its periphery will be

beyond, or farther from the axis than, the minimum level of ink in its pocket and the mouth 45 of the associated delivery member, see Fig. 3, to insure inking of the disc. The disc peripheries adjacent to the axis, located at the inking station S, engage and have driven relationship relative to wire W. Each disc is rotatably mounted on a carrier 88 on which it is turned as the wire rises, the freshly inked surface of the periphery of each disc rising to engage the wire, the discs rotating in the direction of arrow b, Fig. 3, while they are revolved around the wire due to rotation of unit U. The machine shown herein can produce one, two or three helical stripes on the wire, but the invention is not limited to this number of stripes.

In order to complete the disclosure of a striping machine embodying the invention, brief mention will be made of means for changing the angles of the planes of the disc to produce stripes at different angles to the axis, and means to adapt the discs to wires of different diameters.

A ring gear 90 rotatable about the unit meshes with three pinions 91, one for each carrier 88 and turning therewith. Turning of the ring gear relatively to the unit changes the angle of the carriers and discs. Supports 92 hold gear 90 in mesh with its pinions. A second ring gear 93 meshes with pinions 94 screw-threaded on the shanks 95 of the carriers. Each shank passes through a bearing 96 secured to the unit U, and the pinions 91 and 94 for each shank fit snugly between the associated bearing 96 and the unit. When ring gear 93 is turned on the unit its pinions turn and by the screw threads move the carrier and disc radially. This operation is performed while gear 90 is held fixed to the unit by a clamp 97. Clamp 98 holds ring gear 93 in adjusted position on the unit. The shanks are not threaded in the pinions 91 or bearings 96, but are reduced to slide in them when radial adjustments are being made. A key 99 connecting each pinion 91 to its shank is short enough to allow the required radial adjustment.

The ring gears and their pinions are not claimed herein, as they are part of the matter claimed in an application Serial No. 90,392 filed by Donnan on even date herewith.

From the foregoing it will be seen that the invention sets forth simple means by which the ink flowing from a stationary reservoir or tank into an inking pocket can regulate itself so that the proper amount of ink can be automatically maintained in the pocket. The differences in forces exerted at the mouth of each ink delivery tube or member by gravity and the rotating ink in the receiver determines when ink shall flow out of, and when into, the mouth. The receiver rings are complete in themselves, each containing an ink compartment. The ribs or vanes in the compartments help to keep ink in the compartments rotating. The catch wells are not ordinarily occupied by ink, but receive ink from the pockets and compartments when the machine is stopped.

Having thus described the invention it will be seen that changes and modifications of the foregoing specific disclosure may be made without departing from the spirit and scope of the invention.

What is claimed as new is:

1. In a striping machine having a vertical axis along which a wire moves to be striped when the machine is in operation, a striping unit rotating about said axis and having an inking pocket

therein and striping means extending into the pocket a given distance from said axis and striping the wire when the machine is in operation, the unit being closed below said pocket to prevent escape of ink, a stationary reservoir for striping ink above said unit, a stationary ink delivery member having a mouth spaced from said axis by a distance less than said given distance through which ink can flow from said reservoir to said unit, an ink receiver secured to and rotatable with said unit comprising a ring member concentric with said axis and formed with a circular ink compartment therein above said pocket, said compartment having an opening therein extending continuously around said axis opening toward the latter through which said delivery member extends to locate said mouth in said compartment to deliver ink to the latter from said reservoir, and said ink receiver having a vertical duct therein farther from said axis than is said mouth communicating with said pocket and through which ink can flow from said compartment into said pocket to compensate for ink drawn from said pocket due to operation of said striping means.

2. In a striping machine having a vertical axis along which a wire moves continuously to be striped when the machine is in operation, a striping unit rotating about said axis and having an inking pocket therein and striping means in the pocket extending a given distance from said axis striping the wire when the machine operates, the unit being closed below said pocket to hold ink, a stationary reservoir for striping ink having a hollow stationary ink delivery member formed with a mouth spaced from said axis less than said given distance to deliver ink from the reservoir to the unit, an ink receiver secured to the top of the unit and rotatable with the latter comprising a ring member having an ink compartment therein formed with an opening therein extending around said axis and opening toward and concentric with said axis, a wall forming part of said compartment concentric with said axis and farther from the latter than is said opening, said delivery member extending through said opening and said mouth being located in said compartment to deliver ink from said reservoir into said compartment, and said unit having an ink passage therein beyond said wall with reference to said axis communicating with said compartment and pocket through which ink can flow from said compartment down into said pocket to compensate for ink drawn from said pocket incident to operation of said striping means.

55

3. A striping machine as set forth in claim 2 wherein the unit is provided with an ink catch well below and communicating with said inking pocket and wherein all of that part of said catch well which opens into said pocket is nearer said axis than is said mouth of the ink delivery member.

4. A striping machine as set forth in claim 2 wherein part of said inking pocket extends under said striping means to a point nearer said axis than is said mouth.

5. In a striping machine having a vertical axis along which a wire moves to be striped when the machine is in operation, a striping unit rotating about said axis and having an inking pocket therein and striping means extending into the pocket a given distance from said axis and striping the wire as the machine operates, a stationary reservoir for striping ink above said unit, an ink receiver secured to said unit above said pocket and rotating with the unit when the latter rotates and comprising an ink compartment formed with an opening extending continuously around and concentric with and opening toward said axis, a hollow stationary ink delivery member connected to said reservoir having a part thereof extending between said axis and said receiver and having another part thereof extending through said opening into said compartment, said other part of said ink delivery member having an ink delivery mouth within said compartment located at a distance from said axis less than said given distance to deliver ink from said reservoir to said compartment, and said receiver having an ink passage therein connecting said compartment with said pocket located farther from said axis than is said mouth through which ink can flow from said compartment into said pocket to compensate for ink drawn from the pocket by operation of said striping means.
